UNITED STATES PATENT OFFICE.

ALBERT B. HERRICK, OF NEW YORK, N. Y., ASSIGNOR TO MATIE C. MESSLER, OF PAWTUCKET, RHODE ISLAND.

IGNITER.

1,174,145.

Specification of Letters Patent.

Patented Mar. 7, 1916.

Application filed November 29, 1912. Serial No. 733,976.

To all whom it may concern:

Be it known that I, ALBERT B. HERRICK, a citizen of the United States, and a resident of New York, county of New York, and State of New York, have invented a new and useful Improvement in Igniters, (Case B,) of which the following is a specification, the principle of the invention being herein explained and the best mode in which I have contemplated applying that principle, so as to distinguish it from other inventions.

The subject of the present invention is an induction mechanism adapted particularly for use in an igniter which will be attached to an engine cylinder in the position usually taken by the spark plug, the compression of the engine being used to furnish the power necessary to perform the movements which are required in the induction mechanism. In other words, the device is in a sense a self-contained magneto attached to a spark plug and adapted to be automatically operated by the compression of the gases in the cylinder of an internal combustion engine, although it will be understood that other uses for the mechanism will readily suggest themselves.

To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of the various mechanical forms in which the principle of the invention may be used.

In said annexed drawings: Figure 1 is a central vertical section through one form of my invention; Fig. 2 is a section on the line 2—2, in Fig. 1; Fig. 3 is a view in perspective of the induction coil and the contact members attached to the ends of the magnet; Figs. 4 and 5 are end elevations of the mechanism showing the induction coil in its upper and lower position; Fig. 6 is a diagram showing the method of wiring the device; Fig. 7 is a side elevation of a modified form of my invention; Fig. 8 is a view similar to Fig. 7, but showing the induction coil in its raised position; Figs. 9 and 10 are views corresponding to Figs. 7 and 8, showing a third form of the invention, and

Fig. 11 is a section on the line 11—11, in Fig. 1.

In the construction shown in Fig. 1, I attach to a hollow spark plug 1 a brass plate or base member 2 upon which will be mounted the contacts 3 and 4 attached to the ends of a magnet 5. The magnet is preferably laminated or sectional, as shown in Figs. 1 and 2. Upon the top of the members 3 and 4, I attach a second brass plate 6 upon which there is mounted a lubricating cup 7, the construction of which need not be explained in detail. The magnets 5 are preferably of U-shape and extend horizontally around an induction coil 8, consisting preferably of a primary coil 9 only, and a soft iron core 10. The induction coil is provided at its top and bottom with plates 11 and 12 attached to the core. To the bottom plate 12 is attached a piston member 13 slidably mounted in the hollow chamber formed in the spark plug and adapted to be operated by the compression in the engine cylinder. The piston will be lubricated from the oil cup 7 by suitable mechanism. Attached to the piston 13 are a spring arm 14 terminating in a contact 15 and a rod 16 terminating in a contact 17, adapted to normally engage the contact 15, thus forming a closed circuit, as both contact members are suitably connected to the induction coil, the connection being illustrated in Fig. 6. The spring arm 14 extends around the contact 15 and engages a collar 18 slidably mounted upon a rod 19 extending downwardly from the end of the spark plug. The end of the rod 19 is threaded and is engaged by a stop in the form of a nut 20. The spring arm 14 is engaged between the collar 18 and the nut 20, a spring 21 normally retaining the collar 18 in its lower position against the nut 20.

The magnets may be suitably inclosed in a casing (not shown) which will preferably be attached to the members 2 and 5 forming the bottom and top plates respectively of the device. A sleeve 22 is suitably attached to the top and bottom plates and extends vertically between the same inclosing a rod 23 provided with a handle 24 and attached at its lower end by means of a pin 25 to a lever 26 which is pivoted intermediate its ends about a pin 27 mounted in an extension of the bottom member 2. The lever 26 terminates in a yoke 45, each arm of the yoke engaging a pin 28 which is slidably mounted

in the member 2, the pins being attached to the plate 12 at the bottom of the induction coil. An adjusting member 29, in the form of a set screw, is mounted in the top 5 and 5 is adapted to bear against a spring 30, also attached to the top member 5, and adapted to bear against the plate 11 on the top of the induction coil. The action of the spring 30 tends to retain the induction coil in its 10 lower position, shown in Fig. 1, until the induction coil is raised by means of the piston 13 operated by the compression in the cylinder, or until the handle 24 is pushed downward, thus oscillating the lever 26 and 15 operating the induction coil upward through the pins 28.

The core 10 is formed at either end with contact members 32 and 33 which lie in parallel planes, and are directed in oblique directions, thus forming substantially a letter X. The contact members 3 and 4 on the ends of the magnets are formed with complementary contacts 35, 36, 37 and 38, which are adapted to be engaged by the contacts 32 and 33 in the various positions of the induction coil. In the normal position of the induction coil, shown in Fig. 4, the face 39 of the contact 32 engages the face 37 of the contact 4; also the lower face 40 of the contact 33 engages the face 36 of the contact 3. The magnetic circuit is then closed, the flux being from the north pole of the magnet through the induction coil in the direction indicated by the arrow in Fig. 4, and returned to the south pole of the magnet. Upon the operation of the induction coil into its upper position, the contact face 41 of the contact 32 engages the face 35 of the contact 3, while the contact face 33 engages 40 the contact face 37 on the member 4. The direction of the magnetic flux is therefore reversed, the direction now being shown by the arrows in Fig. 5. In this way a very considerable electrical current can be induced, as the current fluctuates from a positive maximum, which is the current induced in the coil as the induction coil is moved into its normal position, to a negative maximum, which is the current induced in the 50 coil as the induction coil is moved into its raised position shown in Fig. 5. As the induction coil is raised, however, the rod 16 is also raised, as well as the spring arm 14. The spring 14 will normally be slightly 55 stronger than the spring 21, so that the contact 15 will remain in engagement with the contact 17 during the first portion of the upward movement of the coil. As soon, however, as the spring 21 is compressed, the 60 rigidity of the same is increased and it becomes stronger than the spring 14. At this point, therefore, the spring arm 14 and consequently the contact 15 will begin to lag and a sharp break will be produced between the contacts 15 and 17, thus producing a

spark between the terminals of the plug. If it is desired to produce a spark when the engine is not running, it is only necessary to depress the handle 24, thus giving the same upward movement to the induction coil as is produced by the compression in the engine cylinder. A current is therefore induced in the induction coil and the operation is exactly as has been described above, the same spark being produced at the terminals of the plug.

In the present mechanism it is unnecessary to use a high tension secondary coil, and I have therefore shown the induction coil as consisting only of a primary coil and a soft iron core. The device shown in Figs. 1 to 6 inclusive, is adapted to operate as a low tension ignition device, in which type of system the circuit is broken in the cylinder, in which case a high tension current is not required to bridge the gap between the spark plug terminals. If desired, however, the mechanism may be used for high tension ignition, in which case a high tension secondary coil will be required.

In Figs. 7 to 10 inclusive, I show alternative forms of construction designed to be used as high tension ignition devices. In Fig. 7 I show a spark plug 50 which is hollowed out to form a chamber 51 in which there will operate a piston 52. The piston 52 is attached to an induction coil 53 provided with a soft iron core, preferably laminated, having contact pieces or teeth 54 and 55 formed at either end of the same. A magnet 56 is provided, extending around the induction coil and being provided with contacts or polar faces 57, 58, 59 and 60, adapted to be magnetically engaged by the teeth on the induction coil when the same is operated. The magnet is suitably attached to a base plate 61 attached to the spark plug 50. The terminals of the spark plugs 62 and 63 are attached, one to the spark plug proper and one to the induction coil, the latter being extended through a tube 64 about which the piston slides. The terminals are therefore maintained at a predetermined distance from each other, which distance is not varied by the action of the induction coil. In the lower position of the induction coil the teeth 54 and 55 on the core of the coil are in engagement with the faces 57 and 60 of the magnet, respectively. Assuming that the poles of the magnet are as represented by the letters N and S in Figs. 7 and 8, the magnetic flux will then pass from the face 57 to the tooth 54 of the core, through the core and back to the magnet through the tooth 55 and face 60. When the induction coil is raised into the position shown in Fig. 8, the magnetic flux passes from the face 59 to the tooth 55, upwardly through the core and back to the magnet through the tooth 54 and face 58, 13

- thus reversing the direction of the flux. The reversing of the direction of the magnetic flux induces a current which is passed through the plug terminals by suitable mechanism. Suitable mechanism for this purpose may be similar to that described in my co-pending application, Serial No. 700,594, filed May 31, 1912, or may be of the construction shown in Figs. 1 and 2.
- 10 In Figs. 9 and 10, I show a third form of the invention in which the arrangement of the teeth on the core and the polar faces on the magnet differ from that shown in the two previous forms. In this form I also 15 show my preferred form of piston member and hollow chamber in the spark plug. The form of the polar faces and the teeth is substantially like that shown in Figs. 7 and 8, except that the magnet is cut away to form 20 the polar faces 90, 91, 92 and 93, which are adapted to be engaged by the projecting teeth 94, 95, 96 and 97 on the core. The direction of the magnetic flux will be reversed by the operation of the induction coil, the 25 direction of the flux being shown by the arrows in Figs. 9 and 10. The spark plug is hollowed out to form an enlarged chamber 100 which is provided with a beveled shoulder 101 at its upper end and an oppositely beveled shoulder 102 at its lower end. The piston is provided with a complementary beveled portion 103 adapted, when the piston is raised, to contact the shoulder 101, thus providing a secure closure of the aperture in the spark plug and preventing the entrance of any of the hot burning gases into the space surrounding the induction coil and the magnets. In this way the life 35 of the magnets and the induction coil is increased, as the action of the hot gases upon the same tends to break down the insulation and to demagnetize the magnets.
- The present invention provides an automatically operating combination of magnet and spark plug in which the induction coil is reciprocated to cause the establishment of a current therein, which is secured by the arrangement of the magnet and the contacts on the magnet and core, the arrangement being such as to cause a reversal 45 of the magnetic flux through the coil. The travel of the coil is slight and the improved type of piston and chamber prevents the escape of any of the burning gas from the 50 engine cylinder.
- Other modes of applying the principle of my invention may be employed instead of the one explained, change being made as regards the mechanism herein disclosed, provided the means stated by any of the following claims or the equivalent of such stated means be employed.
- I therefore particularly point out and distinctly claim as my invention:—
- 60 1. The combination of a hollow spark
- plug adapted to enter an aperture in an engine cylinder; a member mounted in said spark plug and adapted to be actuated by the compression in such engine cylinder; an induction coil including a laminated core 70 provided with spaced contacts at either end, said induction coil being connected to said member in said plug to be operated thereby; a permanent magnet having its poles disposed at either side of said induction coil, 75 each pole being provided with spaced contacts adapted to magnetically engage certain of said contacts on said core; said contacts being so disposed that movement of said induction coil reverses the direction of 80 the magnetic flux through said induction coil; said induction coil being suitably connected to the terminals of said spark plug.
2. The combination of a hollow spark plug adapted to enter an aperture in an engine cylinder; a member mounted in said spark plug and adapted to be actuated by the compression in such engine cylinder; an induction coil including a low tension primary coil and a laminated core, such core 90 being provided with spaced teeth at either end, said induction coil being connected to said member in said plug to be operated thereby; a permanent magnet having its poles disposed at either side of said induction coil, each pole being provided with spaced faces adapted to magnetically engage certain of said teeth on said core; said faces and teeth being so disposed that movement of said induction coil reverses the direction 95 of the magnetic flux through said induction coil; contacting terminals on said spark plug connected to said induction coil; and means operable by the movement of said member in said spark plug and adapted to 100 break the electrical circuit at said terminals.
3. The combination of a hollow spark plug adapted to enter an aperture in an engine cylinder; a member mounted in said spark plug and adapted to be actuated by the compression in such engine cylinder; an induction coil including a low tension primary coil and a laminated core, such core 110 being provided with spaced teeth at either end, said induction coil being connected to said member in said plug to be operated thereby; a permanent laminated magnet having its poles disposed at either side of said induction coil, each pole being provided with spaced faces adapted to engage certain 115 of said teeth on said core; said faces and teeth being so disposed that movement of said induction coil reverses the direction of the magnetic flux through said induction coil; normally contacting terminals for said 120 spark plug, connected to said induction coil, one of said terminals being attached to said member in said spark plug and being operated thereby, thus breaking the electrical circuit at said terminals.

4. The combination of a hollow spark plug provided with a shoulder extending into such hollow portion; a magnet attached to said spark plug; an induction coil reciprocably mounted between the poles of said magnet, means adapted to reverse the direction of magnetic flux through said induction coil upon reciprocation of the same; a piston slidably mounted in said spark plug, 10 said piston being attached to said induction coil and being operable by the compression in the engine cylinder; and a shoulder formed on said piston adapted to engage such shoulder on said spark plug, thereby preventing the leakage of pressure-fluid past said piston.

5. The combination of a hollow spark plug provided with an upwardly beveled concentric shoulder extending into such hollow portion; a magnet attached to said spark plug; an induction coil reciprocably mounted between the poles of said magnet, means adapted to reverse the direction of magnetic flux through said induction coil 25 upon reciprocation of the same; a piston slidably mounted in said spark plug, said piston being attached to said induction coil and being operable by the compression in the engine cylinder; and a similarly beveled 30 disk formed on said piston and adapted upon actuation of said piston to seat against such shoulder on said spark plug, thereby preventing the leakage of gas past said piston.

35 6. The combination of a hollow spark plug adapted to enter an aperture in the engine cylinder; a magnet mounted on said plug; a piston reciprocably mounted in the hollow portion of said spark plug and operated by the compression in the engine cylinder; a low tension induction coil reciprocably mounted between the poles of said magnet and adapted when reciprocated to so engage said poles that a current is induced in said coil, said coil being attached to, and operated by, said piston; a spring arm terminal attached to said piston and connected to said coil; a second rigid terminal attached to said piston, connected to said coil and normally in contact with said spring terminal; and means adapted to restrain said spring arm upon upward movement of said piston, thereby breaking said circuit.

7. The combination of a hollow spark 55 plug adapted to enter an aperture in the engine cylinder; a magnet mounted on said plug; a piston reciprocably mounted in the hollow portion of said spark plug and operated by the compression in the engine cylinder; a low tension induction coil reciprocably mounted between the poles of said magnet and adapted when reciprocated to so engage said poles that a current is induced in said coil, said coil being attached to, and operated by, said piston; a spring

arm terminal attached to said piston and connected to said coil; a second rigid terminal attached to said piston, connected to said coil and normally in contact with said spring terminal; and adjustable means adapted to restrain said spring arm upon upward movement of said piston, thereby breaking said circuit.

8. The combination of a hollow spark plug adapted to enter an aperture in the engine cylinder; a magnet mounted on said plug; a piston reciprocably mounted in the hollow portion of said spark plug and operated by the compression in the engine cylinder, a low tension induction coil reciprocably mounted between the poles of said magnet and adapted when reciprocated to so engage said poles that a current is induced in said coil, said coil being attached to, and operated by, said piston; a spring arm terminal attached to said piston and connected to said coil; a second rigid terminal attached to said piston, connected to said coil and normally in contact with said spring terminal; a threaded rod attached to 80 said plug; the outer end of said spring arm being apertured to loosely engage about said rod; a nut adjustably secured to said rod in contact with said spring arm; and resilient means normally retaining said 85 spring arm in contact with said nut.

9. The combination of a hollow spark plug adapted to enter an aperture in the engine cylinder; a magnet mounted on said plug; a piston reciprocably mounted in the hollow portion of said spark plug and operated by the compression in the engine cylinder; a low tension induction coil reciprocably mounted between the poles of said magnet and adapted when reciprocated to 95 so engage said poles that a current is induced in said coil, said coil being attached to, and operated by, said piston; a spring arm terminal attached to said piston and connected to said coil; a second rigid terminal attached to said piston, connected to said coil and normally in contact with said spring terminal; a threaded rod attached to 100 said plug; the outer end of said spring arm being apertured to loosely engage about said rod; a nut adjustably secured to said rod in contact with said spring arm; a collar slidably mounted on said rod; and a coiled 105 spring disposed about said rod between said plug and said collar, thereby normally retaining said spring arm in contact with said nut.

10. The combination of a hollow spark plug adapted to enter an aperture in the engine cylinder; a magnet mounted on said 115 plug; a piston reciprocably mounted in the hollow portion of said spark plug and operated by the compression in the engine cylinder; a low tension induction coil reciprocably mounted between the poles of said 120 magnet and adapted when reciprocated to so engage said poles that a current is induced in said coil, said coil being attached to, and operated by, said piston; a spring

magnet and adapted when reciprocated to so engage said poles that a current is induced in said coil, said coil being attached to, and operated by, said piston; a spring 5 arm terminal attached to said piston and connected to said coil; a second rigid terminal attached to said piston, connected to said coil and normally in contact with said spring terminal; a threaded rod attached to 10 said plug; the outer end of said spring arm being apertured to loosely engage about said rod; a nut adjustably secured to said rod in contact with said spring arm; a collar slidably mounted on said rod; and a coiled 15 spring disposed about said rod between said plug and said collar, thereby normally retaining said spring arm in contact with said nut, said spring arm being slightly more rigid than said coiled spring, whereby upon 20 upward movement of said piston, said spring arm will remain in contact with said fixed terminal until the tension on said coiled spring becomes greater than the tension on said spring arm.

11. In a sparking device, the combination 25 of a magnet, an induction coil reciprocably mounted in said magnet; sparking points connected to said coil; said coil and magnet being so formed that reciprocation of said coil induces a current therein; and manually operated means adapted to reciprocate 30 said coil.

12. In a sparking device, the combination 35 of a magnet, an induction coil reciprocably mounted in said magnet; sparking points connected to said coil; said coil and magnet being so formed that reciprocation of said coil induces a current therein; a pivoted lever having one end engaging said coil; 40 and means for oscillating said lever, thereby reciprocating said coil.

13. In a sparking device, the combination 45 of a magnet, an induction coil reciprocably

mounted in said magnet; sparking points connected to said coil; said coil and magnet 50 being so formed that reciprocation of said coil induces a current therein; a pivoted lever having one end engaging said coil; and a rod engaging the free end of said lever and adapted when operated to oscillate 55 said lever, thereby reciprocating said coil.

14. In a sparking device, the combination 60 of a magnet, an induction coil reciprocably mounted in said magnet; sparking points connected to said coil; said coil and magnet 65 being so formed that reciprocation of said coil induces a current therein; a pivoted lever having one end engaging said coil; a rod engaging the free end of said lever and adapted when operated to oscillate 70 said lever, thereby reciprocating said coil; and resilient means adapted to return said coil to its normal position.

15. In a sparking device, the combination 75 of a magnet; an induction coil reciprocably mounted in said magnet; sparking points connected to said coil; said coil and magnet being so formed that reciprocation of said coil induces a current therein; a casing 80 inclosing said magnet and coil; a rod slidably mounted in said casing; a lever pivotally attached to said casing intermediate the ends of the same; said lever being engaged at one end by said rod and at the other by said coil, whereby operation of said rod reciprocates said coil; and a spring mounted on said casing and engaging said coil, said spring being adapted to return said coil to its normal position.

Signed by me this 21st day of November, 80
1912.
